UNITED STATES PATENT OFFICE.

FRANK I. MESICK, EMMA P. W. ELLIOT, AND MABEL E. WOODCOCK, OF ALBANY, NEW YORK.

SANITARY COVERING FOR CLOSET-SEATS.

1,108,460.

Specification of Letters Patent.

Patented Aug. 25, 1914.

Application filed April 4, 1914. Serial No. 829,670.

To all whom it may concern:

Be it known that we, FRANK I. MESICK, EMMA P. W. ELLIOT, and MABEL E. WOODCOCK, all being citizens of the United States 5 of America, and each residing at the city of Albany, in the county of Albany and State of New York, have invented certain new and useful Improvements in Sanitary Coverings for Closet-Seats, of which the following is a 10 specification.

Our invention relates to a sanitary covering for closet seats, and the object of our invention is to provide an inexpensive covering which may be readily placed on a 15 closet seat and removed therefrom and which will effectively prevent the transmission of diseases; together with such elements and combinations as are hereinafter more particularly set forth and claimed.

20 We accomplish these objects by means of the mechanism illustrated in the accompanying drawing, in which:

Figure 1 is a transverse section of our invention applied to a closet seat. Fig. 2 is a 25 reverse plan view of our invention.

Similar letters refer to similar parts throughout the several views.

We construct our covering of light, inexpensive material, preferably of paper, although we do not limit ourselves to this material.

The portion, A, of the covering is adapted to cover the closet seat and has at its rear the openings, B, B, with preferably the portion, A, cut at D, D, between the openings, 35 B, B, and the rear edge, C, whereby the hinges on the cover may be pushed through the cuts, D, D, into the openings, B, B. We also secure to the reverse side of the cover,

40 A, a curved strip, E, which may be pasted or otherwise secured along its outer edges to the cover, A, as shown by broken lines in Fig. 2, leaving the strip, E, detached from the cover, A, through a greater part of its

45 extent and permitting the cover to be slipped onto the seat, F, of the closet, G, by causing the forward part of the seat, F, to enter the space between the strip, E, and the cover, A, and occupying the position shown in Fig. 1.

50 The cover, A, may be cut out at H, corre-

sponding to the opening in the closet seat, F, and along the edges of the cut-out portion are a series of slits, h, h, permitting the parts, J, J, of the cover between the slits to be bent downward around the sides of the 55 opening in the seat of the closet, as shown in Fig. 1.

As thus arranged the cover may be very quickly placed in position by the most unskilled person. The arrangement of the 60 cover is such that it is retained both at front and rear, that is, by the front of the seat entering the sack-like formation of the strip, E, in the cover, A, and at the rear by the hinges on the closet seat entering the openings in the cover. The cover is held in position and effectively prevents the person of the user engaging with any portion of the 65 closet seat.

What we claim as our invention and desire 70 to secure by Letters Patent is:—

1. A removable cover for closet seats, comprising a piece of thin, pliable material cut out in the center, provided at one side with openings into which the hinges of the closet 75 seat may be placed; and a strip secured to the outer edge of said piece, forming a sack-like portion into which the front of the closet seat may be placed.

2. A removable cover for closet seats, comprising a piece of thin, pliable material cut out in the center, adapted to cover the closet seat; a curved, thin strip of pliable material cut out in the center secured along its outer edges to the reverse side of said cover, leaving the strip detached from the cover throughout a greater part of its extent, permitting the cover to be slipped onto the seat, the seat occupying the space between the strip and the cover; and said cover provided 85 with openings through which the hinges of the seat pass.

In testimony whereof we have affixed our signatures in presence of two witnesses.

FRANK I. MESICK.

EMMA P. W. ELLIOT.

MABEL E. WOODCOCK.
